UNITED STATES PATENT OFFICE.

CARL G. ALDRICH, OF SOMERVILLE, MASSACHUSETTS, ASSIGNOR TO CONTINENTAL OPTICAL CORPORATION, OF NEW YORK, N. Y., A CORPORATION OF DELAWARE.

EYEGLASS CASE.

Original application filed May 5, 1926, Serial No. 106,918. Divided and this application filed May 26, 1927. Serial No. 194,474.

My invention relates to leather cases or containers such, for example, as are provided and used for holding eyeglasses and spectacles, and particularly to eyeglass cases of that class which are made from leather or other flexible sheet material and comprise a pouch body provided with a closure flap that is fastened to the outer side of the pouch, usually by means of a stud and socket snap fastener.

My invention has for its object to improve the construction of eyeglass cases of the class described and to this end I have provided an eyeglass case having the peculiar features of construction and arrangement of parts set forth in the following description, the several novel features of the invention being particularly pointed out and defined in the claims at the close thereof.

20 In the accompanying drawings:

Figure 1 is an elevation of an eyeglass case constructed in accordance with my invention.

Figure 2 is a section on line 2—2 of Fig. 1.

25 Figure 3 is a section on the line 3—3 of Fig. 1.

Figure 4 is a section on line 4—4 of Fig. 1.

Figure 5 is an elevation, on reduced scale, 20 of the bow frame reinforce hereinafter referred to.

My improved eyeglass case, as herein shown, is made from a single piece of pliable sheet material, preferably leather, one 35 end portion 1 of which is folded back upon the body portion 2 and fastened thereto along its side edges by stitches 3. This forms a pouch of the parts 1 and 2 and having a closure flap 4 integral with the latter, 40 and the two sides of this pouch, adjacent the stitches 3, are molded so as to space the portions 1 and 2 apart as shown in Fig. 2 to permit of easy insertion and removal of the glasses. The shape thus given to the 45 pouch also provides for the reception within the latter of a spring metal reinforcing bow frame 5 that is made so that before insertion into the pouch it is of the expanded shape shown in Fig. 5, and so that when in position within the pouch the two arms 6 thereof are bent toward each other as shown and are always under stress which holds them 50 firmly against the sides of the pouch. The

extremities of the arms 6 are pointed as at 55 8 and bent outwardly as at 7 with the result that the engagement of the points 8 with the pouch prevents the bow frame from slipping out of place. Spines or barbs 9 provided at the sides of the arms 6 also assist in holding the bow frame against displacement, 60 said barbs being pointed toward the free end of the arm so that the latter cannot slip outwardly relatively to the pouch. This construction of the bow frame is fully effective in causing it to hold itself in place 65 against displacement however the case be flexed, twisted, or otherwise manipulated.

The bow frame 5 not only serves to maintain the case in shape against outside pressure around three sides thereof, but its chief 70 office is to render the case practically unbendable laterally, at least to an extent sufficient to cause breakage of the glasses.

It is not new in this art, broadly speaking, 75 to provide an eyeglass case with an interior metal bow reinforcing frame, for such has been incorporated within eyeglass cases having rounded or curved sides, the latter pocketing the correspondingly shaped end portions of the bow frame so as to hold it in 80 place. My improved eyeglass case, however, is preferably made approximately oblong or rectangular with straight parallel sides, and the spring bow frame is incorporated within this case under stress which serves 85 to hold the points of the frame, both at the ends and at the sides of the arms, pressed against the side walls of the pouch whereby the frame is positively locked within the latter.

90 The closure flap 4 carries the socket member 10 of the usual snap fastener, said member being riveted, as usual, to the flap. The stud member 11 of the snap fastener is secured in position upon the outer side of the wall 1 of the pouch by means of a tubular rivet 12.

A feature of this invention consists in employing a rivet 12 of greater length than heretofore used, and in utilizing it to secure 100 both the stud member 11 and a bridge block 13 to the wall 1, the former upon the outer side of the wall and the latter upon the inner side thereof.

The bridge block 13 is constructed, as 105 usual, except that it is formed with a hole

through it for the reception of the tubular rivet 12. Also, block 13 serves, as usual, to protect the glasses from injury when the flap 4 is closed down on to wall 1 and pressure is applied to the opposite sides of the pouch to engage the two members of the snap fastener. It will be clear, also, that the bow frame 5, which is preferably a narrow strip of tempered sheet metal, is disposed edgewise with relation to the walls 1 and 2 of the pouch and therefore serves effectively to prevent bending of said pouch laterally. Another function performed by the bow frame is that it is preferably made of about the same width as the interior of the pouch and therefore serves to hold the two side and bottom portions of the latter distended, or in shape.

Reference is hereby made to my co-pending application filed May 5, 1926, Serial No. 106,918 of which this application is a division.

What I claim is:

1. A case comprising a leather pouch and a reinforcing bow frame consisting of a strip of sheet metal fitted within said pouch and provided at its side edges with barbs embedded in the walls of the latter whereby said frame holds itself in place within the pouch and supports the walls thereof that are opposite its edges in spaced-apart relationship.
2. A case comprising a leather pouch and a barbed reinforcing bow frame of spring sheet metal fitted within said pouch under tension with its barbs embedded in walls

of said pouch to hold said frame against displacement relatively thereto.

3. An eyeglass case comprising a leather pouch having a closure flap; a snap fastener whereof the socket member is fastened to said flap and the stud member is fastened to one of the walls of said pouch by a rivet, and a bridge engaging member held in position against the inner side of said wall by said rivet.

4. An eyeglass case comprising a leather pouch having a closure flap; a snap fastener whereof the socket member is fastened to said flap and the stud member is fastened to one of the walls of said pouch by a tubular rivet, and a bridge engaging member fastened in position against the inner side of said wall by said rivet, said member being a block of wood formed with a hole through which said rivet extends.

5. An eyeglass case made from a single piece of flexible leather or the like folded upon itself and having the side edge portions thereof fastened together by stitches to form a pouch, said pouch being molded to fix the two walls thereof in spaced apart relationship; and a barbed metal reinforcing bow frame sprung into position within said pouch with its barbs engaging the walls of the latter, said bow frame being a strip of spring metal having approximately the same width as the interior of the pouch and being disposed edgewise with relation to the front and rear walls of the pouch so as to maintain said walls spaced apart.

CARL G. ALDRICH.
